(57) **CLAIM**

The ornamental design for a visor, as shown and described.

DESCRIPTION

FIG. 1 is a perspective view of a visor according to the present invention;

FIG. 2 is a front view thereof;

FIG. 3 is a rear view thereof;

FIG. 4 is a side view thereof, the other side being a mirror image thereof;

FIG. 5 is a top view thereof;

FIG. 6 is a bottom view thereof; and,

FIG. 7 is a perspective view thereof.

The broken lines shown in FIGS. 1 through 7 are environmental and form no part of the claimed design.
